H. R. HOLDEMAN

ITALIAN EFFECT GRILLE FOR LIGHTING FIXTURES OR SIMILAR ARTICLES

Filed Jan. 21, 1928

Haug Holdeiman
INVENTOR.

UNITED STATES PATENT OFFICE.

HARRY R. HOLDEMAN, OF LOS ANGELES, CALIFORNIA, ASSIGNOR TO THE J. M. FELDMAN CO. INC., OF LOS ANGELES, CALIFORNIA.

DESIGN FOR AN ITALIAN-EFFECT GRILLE FOR LIGHTING FIXTURES OF SIMILAR ARTICLES.

Application filed January 21, 1928. Serial No. 24,970. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for an Italian-Effect Grille for Lighting Fixtures or Similar Articles, of which the following is a specification, reference being had to the accompanying drawing, forming a part thereof.

The figure is a plan view of an Italian effect grille for lighting fixtures or similar articles showing my new design.

I claim:

The ornamental design for an Italian effect grille for lighting fixtures or similar articles as shown.

HARRY R. HOLDEMAN.
